UNITED STATES PATENT OFFICE.

GEORGES FOURFILLET, OF LEONIA, AND EGISTO GIOVANNONI, OF FORT LEE, NEW JERSEY, ASSIGNEES TO UNIVERSAL PICTURES CORPORATION, OF NEW YORK, N. Y., A CORPORATION OF NEW YORK.

FILM-TREATING APPARATUS.

Application filed May 25, 1927. Serial No. 194,042.

This invention relates to an improvement in apparatus for treating films, as, for example, the drying of films after the same have passed through a developing machine. 5 However, this invention has other applications in the film industry, and for this reason it must be clearly understood that its application to a drying cabinet is for purposes of illustration only and is not in any way to be interpreted as limiting our invention.

One of the objects of our invention is the provision of a film treating apparatus, in which means are provided for passing the film through the machine under proper tension at all times. The advantage of such a construction is obvious to those skilled in this art, inasmuch as such a machine will impose only the proper tension on the films at all times, irrespective of atmospheric conditions, temperatures, etc., thereby avoiding breakage of the film due to excess tension, avoiding as well insufficient tension on the film during its travel through the machine, which insufficient tension is likely to cause injury to the film for many reasons well understood by those familiar with the film-treating industry.

In the accompanying drawings, wherein we have illustrated one embodiment of our invention,

Fig. 1 shows our improved apparatus in part sectional elevation;

Fig. 2 is a plan view of the apparatus of Fig. 1;

Fig. 3 is a plan view of the apparatus at the bottom of our improved structure;

Fig. 4 is an end elevation of the take-up mechanism employed at the end of the machine; and

Fig. 5 is a side elevation of the apparatus of Fig. 4.

Referring to the drawings in detail, 1 designates in the present embodiment of our invention a drying cabinet substantially rectangular in form and provided with sliding glass doors 2.

At the bottom of the cabinet we provide, at 3 for the supplying of heated air to the interior of the cabinet, this air being supplied from any suitable source of supply, while exits 4 are provided for this air at the top of the cabinet.

Secured to the rear wall 5 of the cabinet

on a bracket 6 is a roller 7 placed adjacent a slot or opening 8 in the rear wall of the cabinet, this slot or opening being provided for the purpose of permitting of the passage of a film 9 to the interior of the cabinet, the film, it being understood, coming from any suitable source of supply, as, for example, a developing machine.

Within the cabinet 1 we provide a frame structure designated 10, this frame structure being generally rectangular in outline, so as to conform generally to the shape of the drying cabinet. The two side members 11 and 12 at the top of the frame structure 10 are provided with a series of transversely extending supporting shafts 13, these shafts being supported at each end in suitable bearings 14 provided in brackets 15, carried by the frame members. Each shaft is provided with a plurality of independently rotatable film-receiving and supporting rollers 15, which may be composed of bakelite or other suitable material. These rollers are free on the supporting shafts 13 and endwise movement thereof is prevented by collars 16 secured to the shafts.

Intermediate each pair of adjacent shafts 13, and hence intermediate adjacent sets of rollers 15 carried thereby, we provide an idler roller 17, clearly illustrated in Figs. 1 and 2. Each roller is mounted on a pivoted bracket 18, pivoted at 19 to the top of the frame 10, a spring 20 being provided to maintain the roller in proper position on its pivot relatively to the rollers 15. The provision of the bearings 20 permits, of course, the rollers 17 to be moved slightly about the pivots 19 so as to properly control the film 9 in its passage through the machine as will be hereinafter pointed out.

The idler rollers 17 are staggered with respect to each other as indicated in Fig. 2, for example; from which figure it will be seen that one of the idler rollers will be placed adjacent the top frame member 11, while the next idler roller will be located adjacent the top frame member 12. The purpose of this will be pointed out hereinafter.

At the bottom or adjacent the bottom of the cabinet 1, and lying directly beneath the rollers above described, we provide a plurality of transversely extending drive shafts 21, these drive shafts being mounted in suitable bearings provided in the bottom side

members 22 and 23 of the frame 10, the member 22 lying directly beneath the top side member 11, while the member 23 lies directly beneath the top side member 12.

5 One end of each of the drive shafts 21 is provided with a bevel gear 24, each one of these gears meshing with a bevel gear 25 carried by a drive-shaft 26, this latter shaft extending lengthwise of the cabinet. One 10 end of this shaft 26 is suitably geared to a driving motor 27.

Each of the shafts 21 is provided with a plurality of rollers 28 which are similar in construction to the rollers 15 at the top of 15 the cabinet, these rollers preferably being mounted on ball-bearings on the shafts 21. At one end of the shaft 21 adjacent the right-hand end of the cabinet as viewed in Fig. 3, is a driving roller 29, this roller being 20 fixed to the shaft so as to be positively driven thereby. The next shaft 21 is provided with a similar roller 30 fixed to the shaft so as to be positively driven thereby, this roller, however, being mounted at the 25 end of the second drive shaft 21 opposite the end to which the roller 29 is affixed to the first drive shaft 21. This arrangement of driven rollers is continued throughout the machine so that we have a plurality of shafts 30 in the bottom of the cabinet, opposite ends of adjacent shafts being provided with a roller rigidly connected thereto.

The film 9 is threaded through the machine as indicated in Fig. 1, passing over 35 the top of the roller 7 at the outside of the feed end of the cabinet, through the slot 8 in the cabinet over the roller 15 adjacent the top frame member 12 down to the corresponding drive roller 29 on the shaft 21 40 lying directly beneath the roller 15, about this roller and up to the top series of rollers and over the roller 15 adjacent the first mentioned roller 15, and so on until the film has passed over or about all of the rollers 15 45 on the first shaft 13, the film as it passes over the last roller on the shaft 13 and which roller we will designate 31, then being passed over the tension roller 17 from which the film then passes to the roller 15 at the 50 extreme end of the shaft 13, after which the film is passed about the rollers 15 and 28 on the second shaft 13 and the second drive-shaft 21 in the same manner as explained in connection with the first of these two shafts 55 in the cabinet.

Within the cabinet and adjacent the discharge end thereof we provide an upright or standard 32 which is rigidly supported in any suitable fashion, this upright being provided with an extension 33 carrying two spaced rollers 34 and 35. Mounted for vertical movement on the standard 32 is a loop roller 36, the guiding means therefor being designated 37. Attached to the guide 37 is 60 a cable 38, this cable leading from the top

of the guide 37 upwardly about the two rollers 34 and 35 and then downwardly, the end of this cable 38 carrying a counter-weight 39. The film 9 as it leaves the last roller 15 in the upper part of the cabinet, passes 70 downwardly about the loop roller 36, as illustrated in Fig. 1, and then upwardly and out of the cabinet through an orifice or slot 40 in the discharge end thereof, passing over a take-up roller 41 shown in detail in Figs. 75 4 and 5 and mounted at the discharge end of the cabinet, the film from thence passing to wind-up reel 42.

The take-up roller 41 is mounted on a drum 43 carried on a shaft 44 mounted in 80 brackets 45 on the discharge end of the cabinet. The shaft 44 is driven by gears, belt, chain or any other suitable drive, a pulley 46 carried on the shaft being provided for this purpose. The end of the 85 drum 43 projects slightly beyond one face of the pulley 41. Pivoted to this face of the pulley are two brake-bands 47 pivoted at 48, each of these brake-bands at the end opposite the pivot 48 being provided with 90 an ear 49. A spring 50 is attached to these ears and normally draws the brake-bands about the drum 43 so as to connect the drum 43 and pulley 41 for drive as a unit. The ends of the brake-bands 47 are constructed 95 so as to provide a space 51 between them, which receives a hooked brake-releasing member 52 pivoted at 53 on the face of the pulley 41. The brake-releasing member 52 is provided with a tail 54 adapted to engage 100 one of the brake-bands 47, while the main portion of the member will engage the end of the other brake-band 47, so that movement of the brake-releasing member about its pivot will release the brake-bands 47 from 105 the drum 43, thereby permitting the drum 43 to rotate with the take-up roller 41 remaining stationary.

On the inside of the discharge end of the cabinet, or in other convenient location, we 110 provide a mounting 55 in which is pivoted a counter-weight arm 56 provided with a hooked end 57 and with a weight 58 so arranged that the arm 56 will normally tend to assume the position shown in Fig. 5. The 115 end of the counter-weight arm 54 opposite the hooked end is provided with an opening 59 through which is passed the counter-weight cable 38. This cable at the underside of the counter-weight lever 54 is provided 120 with a button or other form of abutment 60 adapted to engage the under-side of the counter-weight lever to raise this end of this lever. At the other side of the lever 56 the cable is provided with a similar member 61, 125 the operation of this member being to depress the end of the counter-weight lever.

When the counter-weight lever 56 is elevated under the action of member 60, the hook 57 thereon will engage the brake-re- 130

leasing member 52 above referred to, so as to permit the take-up roller 41 to come to rest, without stopping the drum 43. On the other hand, when the counter-weight lever 56 5 is depressed into the position shown in Fig. 5, for example, the hook 57 is no longer in engagement with the hook 51, and as a consequence the take-up roller pulley 41 will rotate with the drum 43 as a unit.

10 Lying upon the periphery of the take-up 41 is a pressure spool 62 and the film in its passage toward the wind-up mechanism 42 passes between this spool and the periphery of the take-up roller 41. The spool 15 62 is mounted on a pair of arms 63 pivoted on a stub shaft 64 mounted in a suitable bracket 65 at the front of the cabinet. This shaft 64 is provided with a coil spring 66 so disposed with reference to the arms 63 20 as to exert tension thereon in a direction to press the spool upon the film traveling between it and the periphery of the take-up 41. The pulley 62 is also arranged to have a slight pivotal motion with respect to the 25 supporting arms 63, this motion being permitted by the provision of two arms 67, one on each side of the spool and attached to or receiving the shaft 68, carrying the spool; the rear end of these two arms 67 being provided with a cross member 69 pivoted in a corresponding cross member 70 with which the outer ends of the arm 67 are provided.

It will be seen from the foregoing that if the film 9 is threaded through the 35 machine in the manner above described, in other words, if the film be passed into the drying cabinet and then over and under the top and bottom rollers respectively of the first series of rollers arranged within the 40 cabinet so that the film is trained substantially helically from end to end of the first pair of shafts 13 and 21 and over the tension roller or tension controlling roller 17, then in the opposite direction helically from 45 end to end of the next pair of shafts 13 and 21 and over the next roller 17, finally emerging from the cabinet over the take-up roller 41 and to the wind-up reel 42, operation of the motor 27 driving the shaft 26 will effect 50 a travel of the film through the machine or cabinet. It is to be understood that this drive of the film is independent of the wind-up reel 42 in that the film is not drawn through the machine by this reel. The reel 55 42 actually is driven from the shaft 26 by a slip belt 71 so that as far as the wind-up reel 42 is concerned, should the tension on the film exceed the tension for which the machine is set, the wind-up reel 42 will slip.

60 As above pointed out, one of the principal objects of this invention is to automatically regulate the tension on the film so that the film is never under too great a tension, in which event it might be fractured and, on 65 the other hand, so that the film is never

under too slight a tension, which might mean that the same would slip off the rollers in the drying cabinet. As long as the tension in the film is in accordance with the setting of the machine, the take-up roller 41 and the 70 drum 43 remain locked together by the brake-bands 47. As soon, however, as the loop in the film passing under the roller 36 shortens due to the tension in the film increasing, in other words, due to the film feeding through the machine too slowly, the button or abutment 60 on the cable 38 will engage the end of the counter-weight lever 56, raising the same to cause the hook carried thereby to engage the brake releasing member 80 52, which, it will be understood, normally is running in clockwise direction, as viewed in Fig. 5. This will release the brakes 47, and the take-up roller 41 will cease rotation so as to prevent too great a tension 85 on the film, the drum 43, however, continuing its rotation. The film 9, while it will continue to be fed forward by the rollers in the cabinet, will not feed to the reel 42, now being held between the pressure roller 62 and the periphery of the take-up roller 41, which at this time is stationary. The reel 42, or rather the belt drawing the same, will slip to prevent fracture of the film between 90 the end of the cabinet and the reel. The forward movement of the film through the cabinet, therefore, under these conditions, will again lengthen the loop about the roller 36 until the abutment 61 on the cable 38 depresses the counter-weight lever 56 to release the brake-releasing member 52. At 95 this time the brake bands 47 will again be applied to the drum 43, so that the drum 43 and take-up roller 41 will again be locked together and the film will resume its discharge from the cabinet.

It will be seen, therefore, that we have provided means for effecting the travel of a film through film-treating apparatus while automatically regulating the tension on the 100 film in its passage through the film-treating machine to the wind-up reel, whereby the film is always maintained under the proper tension.

While we have described a specific embodiment of our invention, it is to be understood that various modifications may be made in the construction above described within the purview of this invention.

What we claim is:

1. Film treating apparatus including mechanism for imparting motion to the film, comprising a plurality of shafts arranged in pairs the shafts of each pair being disposed in superposed relation, idler rollers carried by one shaft of each pair, idler rollers and a driven roller carried by the other shaft of each pair, the film being trained over all of said rollers substantially helically from end to end of each pair of shafts, a take-up roller 115 120 125 130

- for receiving the film as it is discharged from the apparatus, and tension-controlling means intermediate said rollers and the wind-up reel and dependent for operation 5 upon the length of film between the rollers adjacent the take-up roller and the take-up roller for controlling the operation of the take-up roller.
2. Film treating apparatus including 10 mechanism for imparting motion to the film, comprising idler rollers and driven rollers over which the film is trained, a take-up roller for receiving the film as it is discharged from the apparatus, and tension-controlling means intermediate the said rollers and said take-up roller, the operation of which is dependent upon the length of film between the rollers adjacent the take-up roller and the take-up roller for preventing operation 15 of the take-up roller when the linear movement of the film through the apparatus varies beyond predetermined limits.
3. Film treating apparatus including 20 mechanism for imparting motion to the film, comprising a plurality of rollers about which the film is trained and caused to advance through the apparatus, a take-up roller, and mechanism intermediate the said rollers and take-up roller for preventing operation of 25 the take-up roller while continuing the advance of the film through the apparatus, when the tension on the film is varied beyond predetermined limits.
4. Film treating apparatus comprising a 30 plurality of rollers about which the film is trained, means for driving certain of said rollers to advance the film through the apparatus, a take-up roller for receiving the film as it is discharged from the apparatus, and means intermediate the wind-up reel and the said rollers for preventing operation of 35 the take-up roller except in predetermined relation to the discharge of film from the apparatus.
5. Film treating apparatus comprising a 40 plurality of rollers about which the film is trained, means for driving certain of said rollers to advance the film through the apparatus, a take-up roller at the discharge 45 end of the apparatus over which the film is passed in its discharge, a roller having bodily movement under which the film is trained in its travel to the take-up roller, the bodily movement of said roller being controlled by the film and controlling said take-up roller to regulate the tension on the film during its passage through the apparatus.
6. Film treating apparatus comprising in 50 combination a plurality of rollers about which the film is trained, means for driving certain of said rollers to effect an advance of the film through the apparatus, a bodily movable roller suspended in a loop in the film adjacent the discharge end of the apparatus, and a take-up roller the operation of which is 55 controlled by said suspended roller for regulating the rate of discharge of material from the apparatus thereby regulating the film tension.
7. Film treating apparatus comprising in 60 combination a plurality of rollers about which the film is trained, tension rollers for maintaining the film in proper contact with said rollers, a roller having bodily movement suspended in a loop in the film adjacent the discharge end of the apparatus, a take-up roller cooperating with said suspended roller and controlling the rate of discharge of the film from the apparatus, movement of the suspended roller automatically varying with variations in speed of travel through the apparatus, and the take-up roller automatically controlling the discharge of the film from the apparatus. 65
8. Film treating apparatus comprising in 70 combination a plurality of shafts arranged in the same horizontal plane, idler rollers carried thereby, a plurality of driven shafts disposed in vertical alignment with respect to said first mentioned shafts, idler 75 rollers on said driven shafts, a driven roller secured to each of said driven shafts, said driven rollers being arranged in staggered relation to each other, tension rollers arranged in staggered relation to each other 80 and interposed between adjacent sets of the first-mentioned idler rollers, the film being trained about all of said rollers to effect an 85 advance of the film through the apparatus, a bodily movable roller adjacent the discharge end of the apparatus suspended in a loop of the film, and a take-up roller the 90 operation of which is dependent upon the length of said film loop, for controlling the discharge of the film from the apparatus. 95
9. Take-up mechanism for film-treating apparatus, comprising a driven drum, a take-up roller over which the film is caused to travel freely mounted on said drum, and 100 brake mechanism controllable by the film for uniting the drum and take-up roller for 105 drive as a unit.
10. Take-up mechanism for film-treating apparatus, comprising a constantly rotating drum, an intermittently operable take-up 110 roller mounted thereon, and means controlled by the film being treated for effecting a union of said drum and take-up roller.
11. Take-up mechanism for film-treating apparatus, comprising in combination a 115 positively driven constantly rotating drum, an intermittently operable take-up roller freely mounted thereon, brake mechanism carried by the take-up roller for uniting the roller and drum, and a bodily movable 120 roller controlled by the film being treated for effecting operation of said brake mechanism.
12. Take-up mechanism for film-treating apparatus, comprising in combination a 125

take-up roller over which the film is trained, a presser roller pivotally mounted and co-operating with the film and take-up roller, a drum on which the take-up roller is freely mounted, a bodily movable roller suspended in a loop in the film in advance of the take-up roller, the position of said bodily movable roller being dependent upon the length of the film loop, and mechanism controlled by the position of said bodily movable roller for effecting a union between the take-up roller and drum.

13. Take-up mechanism for film treating apparatus comprising in combination an intermittently operable take-up roller, a continuous rotatable drum, brake mechanism for uniting the roller and drum, and brake releasing mechanism for releasing said brake to permit the drum to rotate independently of said take-up roller, said brake releasing mechanism being controlled by the film being treated.

14. Take-up mechanism for film-treating

apparatus, comprising in combination a drum, a take-up roller freely mounted thereon, mechanism for effecting a predetermined union of said drum and take-up roller, and a counterweight film-controlled lever for effecting operation of the mechanism for uniting the take-up roller and drum.

15. Take-up mechanism for film-treating apparatus, comprising in combination a drum, a take-up roller freely mounted thereon, brake mechanism, film controlled, for effecting a union of said drum and take-up roller, a presser roller for effecting pressure upon a film passing in contact with the periphery of said take-up roller, said presser roller being spring-pressed into engagement with the film and being mounted to have movement about an axis at right angles to the axis of rotation of the take-up roller.

This specification signed this 23rd day of May, 1927.

GEORGES POURFILLET.
